UNITED STATES PATENT OFFICE.

ISRAEL WILLIAMS, OF LIMA, OHIO.

FLYING MACHINE.

1,408,918.

Specification of Letters Patent.

Patented Mar. 7, 1922.

Application filed January 4, 1919. Serial No. 269,563.

To all whom it may concern:

Be it known that I, ISRAEL WILLIAMS, a citizen of the United States, and a resident of Lima, in the county of Allen and State 5 of Ohio, have invented certain new and useful Improvements in Flying Machines; and I do hereby declare the following to be a full, clear, and exact description of the invention, such as will enable others skilled in 10 the art to which it appertains to make and use the same.

This invention relates to improvements in flying machines,—objects of the invention being to so construct a flying machine or 15 air ship that it shall have great carrying capacity; so that it shall be capable of great speed and yet be capable of being run at slow speed or be capable of being floated in the air without being propelled for 20 wardly; so that it shall be easy and safe to land and easy to launch; so that it may be readily managed while in flight, and so that it shall reduce to a minimum the danger of accidents.

25 With these and other objects in view, the invention consists in certain novel features of construction and combinations and arrangements of parts as hereinafter set forth and pointed out in the claims.

30 In the accompanying drawings; Figure 1 is a view in elevation showing an air ship embodying my improvement; Figure 2 is a front end view, and Figure 3 is a rear end view.

35 1 represents frame-work which may comprise front and rear vertical bars 2—3, top bars 5 and bottom bars 6, and within this framework, several decks 7, 8, 9, 10 and 11 are provided and suitably braced by up- 40 rights, such as shown at 12. The top and bottom bars of the framework are extended beyond the front vertical bars as shown at 13 and 14 and between these extensions, a rudder 15 is located and suitably journaled.

45 This rudder comprises a frame 16 in which the rudder blades are mounted and said frame includes in its structure a vertical shaft 17 mounted in front of the frame-work and in the upper and lower extensions 50 13—14 of the main frame. A bracket 18 is secured to the forward portion of the rudder frame and provides a bearing for the shaft 19 of a forward propeller 20. The shaft 19 is connected, by a knuckle or uni- 55 versal coupling 21 with a driving shaft 22 and the latter is driven from motors 23 lo-

cated on one of the decks. A collar 22^a is secured to the driving shaft 22 and bears against the front end of the frame so that the propelling force of the propeller 20 will 60 be imparted to the latter. In Figure 1 of the drawing I have shown two motors 23, but it will be understood that a greater number may be employed and suitably geared to the shaft 22. By mounting the shaft of the 65 forward propeller in the rudder frame and connecting it with a driving shaft through the medium of a knuckle or universal coupling, the propeller may be shifted with the rudder and thus assist in controlling the 70 direction of travel of the machine.

A horizontal shaft 24 is suitably mounted in the framework approximately in line with the longitudinal axis thereof and preferably in a plane above that of the forward propeller shaft. The mounting of the shaft 24 is such that it is susceptible of slight endwise play, for a purpose which will hereinafter appear. The shaft 24 extends beyond the rear end of the framework and 80 has a bearing in a bracket 25, and this shaft carries a rear propeller 26. A plurality of motors 27 may be located on the deck 8 and geared by suitable belting to the shaft 24 for driving the same and the rear propeller. 85

The rear end of a bar or non-rotary shaft 28 is connected, by a ball-and-socket or other universal coupling (as shown at 29) with the forward end of the rear propeller shaft 24. The bar or shaft 28 extends beyond the 90 forward end of the framework and carries a pinion 30 to mesh with a curved rack 31 which forms part of a frame 32 secured to the front vertical bars of said framework. The frame 32 will thus be caused to take the 95 forward thrust or pressure of the rear propeller, and by shifting the bar or shaft up and down, its angle relatively to the shaft of the rear propeller may be changed, and as the pressure exerted by the rear propeller 100 will be transmitted through the shafts 24—28 to the forward bracket 32, the machine will be guided in a vertical direction according to the adjustment of the shaft 28, and the planes (hereinafter to be described) 105 caused to assume an altered angle to the horizontal and thus the machine may be caused to rise or descend. For the purpose of shifting the bar or shaft 28 as above described, a wheel 33 may be suitably mounted 110 between the decks 8—9 and connected, by a rod 34, with said bar or shaft.

A vertical shaft 35 is mounted centrally in the framework and to this shaft, upper and lower horizontally disposed propellers 36, 37 are secured,—said propellers serving to assist in causing the ascent of the machine; to assist in sustaining the same in the air, and in controlling the speed of descent of the machine,—thus rendering the launching and landing of the machine safe and 10 easily controlled. For the purpose of driving the vertical shaft of the horizontal propellers, a suitable number of motors 38 (three being shown in the drawing) may be employed and suitably geared to said shaft. 15 In order that the lifting power of the horizontal propellers may be transmitted to the framework, a collar 39 may be secured to shaft 35 and adapted to bear upwardly against the upper member 5^a of the framework. 20

For the purpose of sustaining the machine when in flight, a plurality of planes will be employed and in order that they may be controlled cause them to effectually sustain the 25 weight of the machine in the air and balance the machine, at least some of said planes are made in sections, as clearly shown in Figure 3.

A plane 40 is located upon the top of the 30 framework and may be provided with openings 41 so as not to interfere with the access of air to the propeller 36.

A fixed inclined plane 42 is located at the forward end of the frame between the upper 35 frame extension 13 and the upper frame member 5^a. Fixed inclined planes 43—43 are also located between the upper frame member 5^a and the upper deck 11, and fixed inclined planes 44—44 are also located between the decks 7 and 8. Inclined planes 45 are located between the deck 7 and the bottom member 6 of the framework and rigidly secured to both. A fixed inclined plane 42^a 40 is also secured to lower frame extension 14 and a bracket 42^b depending from the lower frame member 6.

Between the decks 8—9, 9—10, and 10—11, 50 three sets of planes 46, 47, 48 are disposed, each of said planes being hinged at one end to one of said decks, and the other ends of the hinged planes the three sets are connected with vertically shiftable bars 49. For the purpose of shifting these bars to change the angle of the hinged planes and thus control the 55 flight of the machine, hand wheels 50 are provided and connected with said shiftable bars by means of links 51.

In order to increase the power of the machine to carry large cargoes and to travel at 60 great speed, I employ pneumatic propelling and lifting instrumentalities, and these will now be explained.

A plurality of fans or blowers 52 is supported on a swinging frame 53 disposed between the decks 7 and 8 and with these

blowers, intake tubes or stacks 53' communicate, said tubes or stacks extending upwardly through the decks 8, 9, 10 and 11 and through the upper frame member 5^a and are open at their upper ends. Discharge pipes 70 54 communicate with the blowers 52 and discharge at the rear end of the machine. The fans or blowers 52 are driven by suitable motors, such as illustrated at 55^a and they serve to take air from the upper part of 75 the machine and discharge the same with sufficient force rearwardly to propel the machine forwardly by the impact of such discharged air against the atmosphere. The operation of the fans or blowers in forcibly ejecting 80 the air rearwardly of the machine will cause a backward pressure against the blowers, and the latter being mounted upon a swinging frame, the pressure may be transmitted to the forward end of the machine. For 85 this purpose, a rod 55 is connected with the several blowers 52 and with this rod, a shaft or rod 56 is loosely connected, the forward end of said shaft or rod being adjustably connected with the forward part of the machine. In effecting such adjustable connection of the shaft or rod 56 with the frame, a pinion 57 is mounted near the forward end of said shaft or rod and meshes with a rack 58 which constitutes the part of a frame 90 59 secured to the front of the frame of the machine. The shaft or rod 56 is connected with the hand wheel 33 by means of a link 60, so that when said wheel is turned, the shaft or rod 56 will be adjusted to properly 100 take the backward thrust or pressure and transmit the same to the front of the machine, said wheel being manipulated by the operator when the angle of inclination of the machine, when in flight, changes. 105

Other blowers 61 driven by motors 62 are disposed between the decks 7—8 and are supported by rods 62' suspended from the upper member 5^a of the framework. Air intake pipes or stacks 63 extend from these 110 blowers to the upper part of the machine, and pipes 64 communicating with said blowers 61 discharge the air with considerable pressure downwardly against the air under the machine. The forcible downward discharge of air from the pipes 64 will serve to cause the machine to rise and a diminution of such pressure will assist in effecting gradual descent of the machine. The backward pressure against the blowers 61 will 115 be in an upward direction and such pressure will be transmitted to the upper part of the machine by the rods 62'.

It will be understood that certain of the decks and planes will be made with suitable 125 openings for the accommodation of the stacks 53—63 and rods 62.

In the space between the lower deck 7 and the bottom member 6 of the frame (which space constitutes the "hold" of the 130

machine) a swinging frame 65 is located and supports blowers as illustrated at 66 Figure 1. Forwardly projecting intake pipes 67 communicate with these blowers, and dis-

5 charge pipes 68 extend rearwardly therefrom and forcibly eject the air rearwardly of the machine to add to the propulsion of the latter. The backward thrust or pressure of the blowers 66 will be transmitted to 10 the forward part of the machine by means of rods such as shown at 69,—the rear ends of said rods being secured to said blowers and their forward ends being secured to the front part of the framework.

15 For the purpose of operating the rudder to steer the machine, a hand wheel 70 may be provided, said wheel having connected therewith, two chains 71—71 which extend in opposite directions from said wheel and 20 after passing over pulleys 72 mounted on the frame, are connected with the rudder. Thus by turning the hand wheel 70 in one direction or the other, sufficient power will be transmitted to the rudder properly to 25 shift the same.

The decks and bottom member of the frame may be provided with separated slats to form floors and the main frame of the machine may be enclosed by wire netting.

30 Legs 73 may be secured to the bottom member of the frame for supporting the machine when at rest upon the ground.

It will be observed that with my improvements all the forwardly propelling force is 35 imparted to the front part of the machine, and that all the lifting or elevating force bears at the top or upper part of the framework. It will also be observed that the upper propeller is located in the space between 40 the upper members 5 and 5^a of the framework and that said upper and lower propellers are disposed in rear of the fixed planes 42 and 42^a respectively,—which planes form parts of the framework. Any 45 suitable means may be provided for controlling the motors and blowers.

Various changes might be made in the details of construction of my invention without departing from the spirit thereof or 50 limiting its scope and hence I do not wish to restrict myself to the precise details herein set forth.

Having fully described my invention, what I claim as new and desire to secure 55 by Letters-Patent, is:—

1. In a flying machine, the combination of a frame, a blower, means for operating the blower, an intake stack communicating with the blower and extending to the upper 60 portion of the frame, a discharge pipe communicating with said blower and arranged to project air downwardly from the machine, and a rod suspended from the upper

portion of the machine and secured to said blower, whereby the back pressure against 65 the blower will be transmitted to the upper portion of the frame.

2. In a flying machine, the combination of a frame, a blower, means for movably mounting said blower, means for operating 70 the blower, an intake pipe for the blower, a rearwardly projecting discharge pipe communicating with the blower, and means for transmitting back pressure against the movable blower to the forward part of the frame. 75

3. In a flying machine, the combination of a main frame, a swinging frame mounted therein, a blower mounted on said swinging frame, an intake for the blower, means for operating the blower, a discharge pipe communicating with the blower and adapted to project air rearwardly of the machine, and means connecting said blower and swinging frame with the forward part of the machine, whereby back pressure on said blower 85 will be transmitted to the forward part of the main frame.

4. In a flying machine, the combination of a frame, a swinging frame mounted therein, a blower mounted on said swinging frame, 90 an intake for said blower, a discharge pipe connected with said blower and extending toward the rear end of the machine, a rod having its rear end loosely connected with said blower, means adjustably connecting 95 said rod with the forward part of the frame, and manually operable means for adjusting said rod up and down.

5. In a flying machine, the combination of a frame, a rear propeller, a shaft for said 100 propeller, means for driving said shaft, a rod loosely connected with the propeller shaft and adjustably connected with the forward portion of the frame, and manually operable means for adjusting said rod 105 up and down to change its angle relatively to the propeller shaft.

6. In a flying machine, the combination of a main frame, a rear propeller, a shaft therefor, means for driving the propeller 110 shaft, a forward frame secured to the main frame and having a rack bar, a rod loosely connected with the propeller shaft and extending to the rack bar of said forward frame, a pinion carried by said rod to mesh 115 with said rack bar, and manually operable means connected with said rod to adjust the same up and down.

In testimony whereof, I have signed this specification in the presence of two subscribing witnesses. 120
